RECOIL MECHANISM

Clarence E. Simpson, Springfield, Mass.

Application April 20, 1942, Serial No. 439,658

8 Claims. (Cl. 42—4)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a shock absorbing mechanism particularly adapted for use as a recoil mechanism for a firearm.

It is an object of this invention to provide an improved recoil mechanism for a firearm particularly adapted for mounting beneath the barrel of the firearm. Another object of this invention is to provide an improved recoil mechanism of a firearm which includes a breech operating rod within its assemblage. Another object of this invention is to provide an improved recoil mechanism which will effectively and efficiently absorb the recoil forces of a firearm so as to permit shoulder firing of firearms of .60 caliber or larger.

Another object of this invention is to produce a hydraulic energy absorption means effective for energy absorption in two directions wherein the amount and rate of energy absorption for either direction may be independently and conveniently changed.

Another object of this invention is to provide an improved recoil mechanism for a firearm which utilizes a combination of spring and hydraulic energy absorption means.

A further object of this invention is to provide an improved recoil mechanism which also operates a breech closing mechanism; the recoil mechanism being effective to absorb both recoil and counter-recoil shocks by a combination of spring and hydraulic absorption means.

A particular object of this invention is to provide an improved recoil mechanism for a firearm which may be quickly and easily disassembled from such firearm as a unit. It is a further object of this invention to provide a recoil mechanism which may be readily disassembled into its component parts with the use of a minimum number of conventional tools.

The specific nature of the invention as well as other objects and advantages thereof will clearly appear from a description of a preferred embodiment as shown in the accompanying drawings in which:

Fig. 1 is a longitudinal sectional view of the improved recoil mechanism assembled on the barrel of a firearm.

Fig. 2 is the section taken along the plane 2—2 of Fig. 1.

Fig. 3 is the section taken along the plane 3—3 of Fig. 1.

Fig. 4 is the section taken along the plane 4—4 of Fig. 1.

Fig. 5 is a sectional view of the piston member utilized in the hydraulic cylinder shown in Fig. 1.

5 Fig. 6 is an outline view of a split washer utilized in the assembly of the hydraulic cylinder within the recoil mechanism.

Fig. 7 is a side elevational view showing the latching relation between the barrel and the breech extension member prior to firing of a cartridge while Fig. 8 is a similar view showing the latching relation just prior to completion of the counter-recoil movement of the barrel, and

10 Fig. 9 is an enlarged sectional view of an embodiment of the piston and cylinder providing unequal energy absorption on the recoil and counter-recoil movements.

15 Referring to Fig. 1, the improved recoil mechanism A is shown in assembled relation on the barrel B of a firearm. While this recoil mechanism is preferably utilized on a .60 caliber rifle, it will be understood that this is merely a preferred application and its application to other calibers of firearms may be readily accomplished by mere change of the size or strength of its components.

20 The recoil mechanism is roughly cylindrical in shape and is particularly adapted for mounting beneath the barrel B although it should be understood that other mounting positions with respect to the barrel are possible and that only a preferred embodiment is shown. A long hollow cylindrical recoil tube 1 extends throughout the length of the recoil mechanism and is rigidly secured at its rear end to the barrel B by means of a fitting 2.

25 The fitting 2 (Fig. 2) comprises a unitary structure having a large cylindrical opening 3 through which the barrel may be inserted and a transversely extending bifurcated portion 4 defining a smaller semicylindrical opening 4a between fork-like extensions 4b and 4c. The large opening 3 is provided with interior threads 3a and a shoulder 3b which cooperate with threads 3c and shoulder 3d on the barrel B to detachably secure the fitting 2 to the barrel.

30 A bushing 1 is provided having one end detachably secured within the end of recoil tube 1 as by means of the threads 1a which engage interior threads 1a within the tube 1. At the central part of the bushing 1, at the end of the thread 1a, there is provided a flange 1e which is of larger diameter than the opening 4a and tube 1. By screwing the bushing 1 into the end of tube 1, the collar 1e is thereby brought into engagement with the end of tube 1. The other

end of bushing 1 is of suitable diameter to enter the opening 4a by passage between the extensions 4b and 4c of the bifurcated portion 4. The bushing 1 is snugly supported in the opening 4a by means of a cylindrical nut member 7c which is screwed on to the threads 1d on the end of the bushing. The head of this nut member 7c enters a countersunk portion 4d surrounding the opening 4a of fitting 2. In this position, the flange 1e abuts against the front end of the portion 4 of fitting 2. Thus, the bushing 1, and hence the tube 1, is rigidly supported within the opening 4a by tightening of the cylindrical nut 7c. It is apparent that by backing off the cylindrical nut 7c, the bushing 1, and hence the end of recoil tube 1, may be dropped out of the fitting 2, or conversely, the barrel may be raised with respect to the recoil mechanism and freed from engagement therewith.

On the forward end of the tube 1, a collar 6 is snugly mounted. The collar 6 has a large diameter portion 6a and a front smaller diameter portion 6b. A bolt member 5 is threaded into the tube 1 and by means of its projecting head 5a prevents the collar 6 from slipping off the end of tube 1. The outer periphery of portion 6a of the collar 6 is given a smooth finish. This cylindrical surface slides in a bearing surface provided by the inside surface of a surrounding hollow cylinder 8. The hollow cylinder 8 surrounds the tube 1 for a substantial portion of its length and is supported at its rear end by an inserted threaded cylindrical projection 10 of a hollow frame member 9. This frame member 9 is connected with the stationary portions of the firearm in a manner not shown. In a shoulder weapon, for example, the frame member 9 will be rigidly connected to that portion of the firearm which engages the shoulder of the operator. Since the barrel generally has no other rigid connection with the stationary portions of the gun, the recoil or breech closing shocks produced by the discharge and loading of a cartridge respectively must be substantially absorbed before transmittal to the frame member 9.

The front end of the bearing cylinder 8, and hence the tube 1, is supported by threaded engagement with the walls 11a of a surrounding cup shaped member 11. This member 11 has a transverse extending hollow cylindrical portion 12 which is slipped over the barrel B supporting the front end of the recoil mechanism thereby.

The interior surface of the opening 12 is provided with an unusual configuration which may be best described by separately considering the top and bottom semi-cylindrical portions formed by division of the opening 12 by an imaginary horizontal plane. The bottom portion then has a rear half surface 12a of cylindrical shape with such diameter as to closely engage the barrel B. The front half surface 12b is of a semi-conical shape, increasing in diameter towards its front. The top semi-cylindrical portion of opening 12 is likewise provided with a cylindrical surface 12c engaging the barrel B, and a semi-conical surface 12d. However, the location of these top surfaces is exactly reversed with respect to the bottom surfaces; i. e., the cylindrical surface 12c is at the front and the semi-conical surface 12d is at the rear, with the diameter of the cone increasing toward the rear. With this construction, the barrel B will freely slide in a horizontal plane within opening 12, engaging cylindrical surfaces 12a and 12c. At the same time, it is possible to pivot the barrel clockwise (as viewed

in Fig. 1) within the opening 12, the extent of the pivoting being limited by the semi-conical surfaces. Such pivotal movement of the barrel, of course, cannot be accomplished until nut member 7c is backed off, permitting the fitting 2 to be disengaged from the bushing 1 by the pivotal movement. After pivoting the barrel B, it can be withdrawn through the opening 12 and thus be entirely separated from the recoil mechanism A.

A hole 11c is provided in the base 11b of the cup-shaped member 11. Into this hole the front portion 6b of collar 6 is permitted to enter. It should be emphasized that the base 11b does not act as a stop for longitudinal movement of the tube 1 to the front. When the barrel is in its most forward position permitted by the breech mechanism (not shown), there is slight clearance between base 11b and collar 6a.

20 A recoil spring 14 is mounted within and supported by the bearing cylinder 8, and operates between the end of projection 10 of the frame 9 and the rear side of collar member 6. Thus, movement to the rear of tube 1, and hence of the barrel B, is yieldingly resisted by the spring 14.

25 A hydraulic absorption apparatus 15 is also provided. This apparatus comprises a hollow cylindrical container 16 which surrounds the rear portion of the tube 1 and extends about halfway within the spring 14. The cylinder 16 is supported by the interior cylindrical surface of frame member 9. Only a small portion 16g of the cylinder surface within the frame member acts as a supporting surface, the remaining surface being of reduced diameter. Adjacent the end of cylinder surface 16g, there are provided unitarily formed lugs 16a, 16b, 16c, 16d, 16e, and 16f disposed around the periphery of cylinder 16. Longitudinal grooves 9a, 9b, 9c, 9d, 9e, and 9f are provided in the interior surface of frame member 9.

30 These grooves permit passage of the lugs 16a, 16b, 16c, 16d, 16e, and 16f when cylinder 16 is inserted in frame member 9 from the front. A slight rotation of the cylinder 16 after insertion in frame member 9 thus makes the lugs 16a, 16b, 16c, 16d, 16e, and 16f abut against the end of the frame member 9 limiting frontal movement of the cylinder 16 with respect to the frame. Rearward movement of the cylinder 16 is prevented by a

35 washer 26 which is inserted in a cylindrical recess 10a in the end of frame extension 10. In this position, the washer 26 engages the external shoulder 16j formed by the end of reduced diameter portion 16h provided on cylinder 16. Thus the cylinder 16 is secured to frame member 9 so far as relative longitudinal movement is concerned. The washer 26 may be made in two half pieces 26a and 26b (Fig. 6) for convenient assembly around cylinder 16.

40 60 At each end of the cylinder 16 a bearing 17 is inserted and suitably secured therein as by threads 17g. These bearings have relative small interior bearing surfaces 17a engaging the tube 1. The bearings 17 are each provided with a cylindrical extension 17b projecting within the container cylinder 16. The inner surfaces 17c of the extensions 17b are tapered, the diameter increasing toward the center of cylinder 16. The minimum diameter of this tapered portion is equal to the minimum diameter of a piston 18 which is shaped like a collar and is detachably secured as by the threads 18d to the portion of the tube 1 intermediate the bearings. The transition surface between the end of taper 17c and bearing surface 17a provides a radial end wall 17d. The

position of the piston 18 on the tube 1 and the distance between the opposing end walls 17d of the tapered portions 17c are such that in the closed breech position of the barrel, a small clearance exists between one side of the piston member and the end 17d of the front bearing 17, while in the full recoil position of the barrel, a small clearance exists between the other side of the piston 18 and the end 17d of the rear bearing.

The chamber defined by the bearing ends 17d, the exterior of tube 1, and the interior of container cylinder 16 is filled with a suitable hydraulic fluid. Leakage of the hydraulic fluid out through the bearing 17 is prevented by inserts of suitable packing material 19 held in a recess 17e of the bearings 17 by a hollow threaded bushing 20 which cooperates with interior threads 17f provided in the extremities in the bearings 17.

The peripheral surface of the piston 18 is preferably provided with oppositely directed angular cuts 18a and 18b respectively parallel to the tapered surfaces 17c of the front and rear bearings 17. Very little resistance to the movement of the piston 18 will be encountered in the intermediate range of its movement due to the large clearance provided between the surfaces 18a and 18b and the interior of cylinder 16. It will be apparent, however, that as the tube 1 approaches either of its two extreme positions, a hydraulic force gradually increasing in magnitude will oppose such motion as the tapered piston member 18 is brought within the tapered walls 17c of the bearing 17.

Extending through the hollow interior of tube 1, there is mounted the breech operating rod 21. This rod is connected at its rear end to a member 22 constituting an extension of the breech mechanism (not shown). The rod 21 is supported at its rear end by an interior bearing surface provided in the hollow bushing 7. On the front end of rod 21, a collar 23 is fastened and the exterior cylindrical surface of this collar 23 slidably engages the interior surface of the tube 1. The movement to the front of the rod 21 is limited by the breech extension 22. The breech operating spring 24 is inserted in the space defined between the interior surface of the tube 1 and the exterior surface of the rod 21. The spring operates between the end of bushing 7 and the side of collar 23.

Any breech mechanism that will be forced to the rear by the recoil movement of the barrel may be utilized with the described recoil mechanism and accordingly no specific breech mechanism is shown. The breech extension 22 is suitably secured to such breech mechanism.

A latch 30 (Figs. 7 and 8) is provided to coordinate the counter-recoil movement of the breech extension 22, and hence the breech mechanism with the counter-recoil movement of the barrel B. The latch 30 comprises a bar pivoted at its center on a pin 31 transversely mounted in the frame 9 of the firearm between the barrel B and breech extension 22. A second transverse pin 32 acts as a stop to pivotal movement of the latch 30 and prevents the end of latch 30 from hitting the barrel B. A spring 33 exerts a force biasing the latch 30 against the stop 32. The top end of latch 30 is rounded and is depressed by a projection 34 on the barrel B when the barrel is in its firing position as shown in Fig. 7.

A collar 35 is provided on breech extension 22. This collar has an inclined surface 35a

which engages the bottom end surface of latch 30 when the breech extension 22 is in its full recoil position (Fig. 8). The breech extension 22 and hence the breech is thereby latched in full recoil position until the barrel B completes its counter-recoil movement, whereupon projection 34 on the barrel depresses the top end of latch 30, hence raising the bottom end of the latch, freeing collar 35 and permitting the breech extension 22 to complete its counter-recoil movement, hence closing the breech.

In operation, the recoil forces following the firing of a cartridge start the barrel moving rapidly to the rear or to the left as viewed in Fig. 1. This movement is transmitted to the hollow tube 1 by the fitting 2 and bushing 7. The movement of tube 1 results in the compression of the recoil spring 14, through engagement of the head 5a of the bolt member 5 with the collar 6. Since the breech extension 22 moves with the barrel in its recoil, the breech operating rod 21 is also moved to the rear concurrently with the barrel. Thus the spring 24 is not substantially compressed. The piston 18 is moved out of the front bearing 17 by movement of tube 1 and approaches the rear bearing 17. Very little hydraulic resistance to this movement is encountered until the piston enters the tapered portion 17c of the left hand bearing 17. Then the hydraulic resistance to further recoil movement is gradually increased, the rate of increase being dependent upon the slope of the surfaces 17c and 18b. The amount of energy hydraulically absorbed also depends on the slope of the taper. Just prior to the piston 18 reaching its extreme recoil position near the end 17d, the hydraulic resistance will be very great due to the small clearance provided for the escape of the hydraulic fluid between the piston surface 18b of the piston 18 and the surface 17c of the bearing 17. The energy thus absorbed by the spring 14 and the hydraulic mechanism 15 will reduce the recoil shock upon the stationary portion of the gun to a satisfactory magnitude.

The initial movement of the barrel removes extension 34 from engagement with the top end of latch 30, permitting counterclockwise rotation of the latch by spring 33 until the stop 32 is engaged. In this position the latch 30 engages the collar 35 on breech extension 22 when that member reaches its full recoil position, holding breech extension 22 in the full recoil position.

The barrel is now returned to firing position by means of the energy stored in the compressed spring 14. The hydraulic mechanism 15 operates on this counter-recoil movement to reduce the shock inherent at the end of this movement. In this case, the piston 18 does not build up any hydraulic resistance to the movement to the front until it enters the tapered portion 17c of the front bearing 17, then the hydraulic resistance is built up in the same manner as described for the recoil movement.

A very desirable feature of this construction lies in the fact that since the breech extension 22 is held latched by latch 30 in its full recoil position, thereby preventing the return of the breech rod 21 until the barrel has substantially completed its counter-recoil movement, the effect will be to compress the spring 24. This compression has several desirable features in that it provides an additional energy absorption means for reducing the shock involved in the counter-recoil movement of the barrel, while at the same

time providing a positive breech closing force, namely, the spring 24, substantially independent of the recoil spring 14 and the hydraulic energy absorption apparatus 15. The possibility of only partial closing of the breech mechanism is thus reduced.

It should be pointed out that the amount of hydraulic absorption with respect to the spring absorption can be readily adjusted by inserting bearing members 17 having different degrees of taper of the surface 17c and of course providing a piston 18 with correspondingly tapered surfaces 18a and 18b. In a similar manner, the hydraulic absorption on the counter-recoil movement can be made greater or less than the absorption during the recoil movement by inserting a bearing 17 in the front position having a different slope of surface 17c than the bearing in the rear position.

The convenient method by which a recoil mechanism embodying the features of this invention may be disassembled from the barrel of the firearm has already been pointed out. Thus the barrel is made available for cleaning merely by backing off the cylindrical nut 1c and pivoting the barrel clockwise to engage the tapered surfaces 12b and 12d of the opening 12. The breech end of the barrel is thus raised above the breech mechanism (not shown) and the barrel may slide to the rear out of engagement with the opening 12 of the supporting member 11.

The entire recoil mechanism may be readily assembled or disassembled through the use of ordinary wrenches. In the disassembly operation, the barrel B is disengaged from the other parts of the apparatus in the manner described. The cylinder 8 is then unscrewed from the extension 10 of the frame member 9, and the cylinder 8, still screwed to the supporting member 11, is disengaged from the apparatus. The bolt 5 is then unscrewed from the end of the tube 1, permitting the collar 6 to be slipped off the end of the tube, thus permitting the spring 14 to be removed. The cylinder 16 is then rotated slightly to bring the lugs 16a, 16b, 16c, 16d, 16e, and 16f into engagement with the longitudinal grooves 9a, 9b, 9c, 9d, 9e, and 9f. The cylinder 16 and its connected parts, namely, the bearing 17 and the bushings 20, may then be pulled through the frame member 9, the bearing 17 and the bushings 20 sliding on the tube 1. Having cleared the frame member 9, the parts of the hydraulic absorption mechanism may then be readily unscrewed and separated from the cylinder 16. This, of course, releases the hydraulic fluid contained therein. If further disassembly is desired, the breech operating rod 21 may be unscrewed from its connection with the breech mechanism 22, and the rod 21 is thereby freed for withdrawal from the recoil tube 1. The spring 24 may thereby be removed. The last disassembly operations may be the unscrewing of the bushing 7 from the end of the tube 1 and the unscrewing of the cylinder 8, from the supporting member 11.

Assembly of the apparatus is quickly accomplished, in general by reversing the assembly steps. One departure, however, should be mentioned, and that is that the supporting member 11 should be screwed to the end of the cylinder 8, and then the collar 6 and the spring inserted within the cylinder. Then this assembly should be installed by screwing the cylinder 8 onto the extending member 10 of the frame. By proceeding in this manner, the heavy spring 14 is very easily handled; and furthermore, the possibility

of deforming it during the assembling operation is reduced. The bolt 5 should not be inserted in the end of the tube 1 until after the barrel has been reassembled. Then tightening of the bolt 5 will have the effect of forcing the collar 6 back a slight distance on the tube 1, sufficient to provide clearance between the collar and the base 11b of the supporting member.

I claim:

10. 1. In a recoil absorption mechanism for a firearm, a hydraulic energy absorption means comprising a recoiling member, a stationary shell surrounding a portion of said recoiling member, bearing members mounted in each end of said shell and sealing the space between said shell and said recoiling member to define a fluid chamber, an annular piston mounted on said recoiling member intermediate said bearing members, said piston having two oppositely sloped annular surfaces, said slopes being unequal, and a parallel sloped interior surface on each bearing member closely surrounding the adjacent sloped piston surface when said recoiling member approaches either of its extreme positions of movement, whereby greater hydraulic energy absorption occurs for one direction of movement of the recoiling member than the other direction.
2. In a firearm having a recoiling barrel and a breech mechanism movable therewith, a recoil mechanism comprising a tube connected to the recoiling barrel of the firearm, resilient means surrounding said tube and arranged to oppose the rearward movement of said tube, a rod mounted for movement within said tube and having one end connected to the breech mechanism, and a spring surrounding said rod and arranged to oppose separation of the barrel and breech mechanism.
3. In a firearm having a recoiling barrel and a breech mechanism movable therewith, a recoil mechanism comprising a tube connected to the recoiling barrel of the firearm, resilient means surrounding said tube and arranged to oppose rearward movement of said tube, stationary hydraulic means surrounding part of said tube and operating to resist movement of said tube, a rod mounted for movement within said tube and having one end connected to the breech mechanism, and a spring surrounding said rod and arranged to resist relative movement of said tube with respect to said rod and thereby oppose separation of the barrel and the breech mechanism.
4. In a firearm having a recoiling barrel and a breech mechanism movable therewith, a tube connected to said recoiling barrel, a first resilient means surrounding said tube and opposing the rearward movement of said tube, a rod connected to said breech mechanism and mounted for movement within said tube, a second resilient means opposing frontal movement of said tube relative to said rod; and means latching the breech mechanism in opened position until the barrel completes its counter-recoil movement whereby the second resilient means is compressed to provide a breech closing force.
5. In a firearm having a recoiling barrel and a breech mechanism movable therewith, a tube connected to said recoiling barrel, a first cylindrical spring surrounding said tube and connected between said tube and a stationary part of the firearm to oppose the rearward movement of said tube, a rod mounted for movement within said tube and having one end connected to said breech mechanism, a second cylindrical spring mounted around said rod and arranged to

oppose frontal movement of said tube relative to said rod, and means latching the breech mechanism in opened position until the barrel completes its counter-recoil movement whereby the second cylindrical spring is compressed to provide a breech closing force.

6. In a firearm having a recoiling barrel and a breech mechanism movable therewith, a tube, connected to said recoiling barrel, a first resilient means surrounding said tube and opposing the rearward movement of said tube, a stationary hydraulic cylinder surrounding said tube, an annular piston mounted on said tube cooperating with the hydraulic cylinder surrounding the tube to hydraulically oppose movement of the tube in either direction of movement, a rod connected to said breech mechanism and mounted for movement within said tube, a second resilient means opposing frontal movement of said tube relative to said rod; and means latching the breech mechanism in opened position until the barrel completes its counter-recoil movement whereby the second resilient means is compressed to provide a breech closing force.

7. In a firearm having a recoiling barrel and a breech mechanism movable therewith, a tube connected to said recoiling barrel, a first cylindrical spring surrounding said tube and connected between said tube and a stationary part of the firearm to oppose the rearward movement

of said tube, a stationary hydraulic cylinder surrounding said tube, an annular piston mounted on said tube cooperating with the hydraulic cylinder surrounding the tube to hydraulically oppose movement of the tube in either direction of movement, a rod mounted for movement within said tube and having one extending end connected to said breech mechanism, a second cylindrical spring mounted around said rod and arranged to oppose frontal movement of said tube relative to said rod, and means latching the breech mechanism in opened position until the barrel completes its counter-recoil movement whereby the second cylindrical spring is compressed to provide a breech closing force.

8. In a firearm, having a recoiling barrel and a stationary recoil absorption mechanism, bifurcated means detachably securing one end of the recoil mechanism in spaced relationship to the barrel, and barrel supporting means at the other end of the recoil mechanism comprising a bracket having a portion arranged to receive said recoil absorption mechanism and another transversely extending portion comprising a collar, said collar having interior bearing surfaces arranged to engage the barrel in its recoil movements and inclined surfaces arranged to permit pivotal movement of the barrel within the collar and withdrawal of the barrel through the collar.

CLARENCE E. SIMPSON.
